COMBINED DOOR AND WINDOW REGULATING SYSTEM FOR MOTOR VEHICLES

David T. Ayers, Jr., Richmond, Va., assignor to Automatic Shifters, Inc., Richmond, Va., a corporation of Virginia

Application January 3, 1951, Serial No. 204,207

16 Claims. (Cl. 268—19)

This invention relates to a combined door and window regulating system for motor vehicles.

An important object of the present invention is to provide a combined door locking and window regulating system for motor vehicles wherein the locking of the vehicle doors cooperates with a window control system so that it is merely necessary to close one push button switch, leave the vehicle and close the door, whereupon all four doors of the vehicle are locked and all of the windows automatically run to closed position.

A further object is to provide such a novel combined system of such nature that when the vehicle is to be locked, the driver, for example, will open the left hand front door by operation of the inside door handle, step out of the vehicle and press the button for the switch of such door, and then close the door behind him, whereupon all four doors will be locked and all of the windows will move to closed position.

A further object is to provide such a system wherein the door operating mechanisms are individually controllable from within the vehicle in accordance with conventional practice, wholly independently of the door locking system, but wherein the systems become interdependent when the doors are to be locked, as referred to above, so that each window operating mechanism automatically becomes operative when the driver steps from the vehicle and presses the single button referred to, whereupon all four doors are automatically locked against entrance from the outside, and wherein all of the windows of the vehicle, regardless of their previous positions, will be completely closed if they are not already closed.

A further object is to provide such a combined system wherein the window regulating devices, normally individually controlled from inside of the vehicle, are rendered independent of the door locking system when they are to be individually controlled, through the medium of door operated switches of such character that when the doors are closed, the window regulating system is wholly independent of the door locking system, but wherein, when the doors are open, such door switches are closed to render the window regulating system an operative entity with the door locking mechanism so that if one of the push buttons for the door locking system is operated, all of the doors will be locked and the windows will be closed.

A further object is to provide a combined system of the character referred to wherein the window regulating system, regardless of the particular type of power means employed for operating the windows, can be made automatically dependent upon the locking of the doors in accordance with the mode of operation referred to above.

A further object is to provide a novel combined system of the character referred to wherein the locking of the vehicle doors by pressing one of the control push buttons as the driver leaves the vehicle automatically initiates operation of the window lifting mechanism, and wherein means is provided for automatically rendering the window lift mechanism inoperative after the windows have moved to closed positions.

A further object is to provide a novel improvement in the door locking system per se which eliminates the use of the relatively expensive cam means employed for this purpose, whereby the operator of a vehicle can lock the doors from the outside while driving the vehicle with the ignition switch turned on, but wherein the locking system is inoperative if the ignition switch is turned off and the key left in the ignition switch.

2

Other objects and advantages of the present invention will become apparent during the course of the following description.

In the drawings, I have shown two embodiments of the invention. In this showing,

Figure 1 is a diagrammatic showing of one form of system employing reversible electric motors as the window regulating means,

Figure 2 is a similar view of a modified form of one portion of the system,

Figure 3 is a schematic showing of the mechanical means driven by an electric motor for raising and lowering a window,

Figure 4 is a diagrammatic showing similar to Figure 1, showing the vehicle windows equipped with hydraulic window regulating motors,

Figure 5 is a perspective view of a locking mechanism for one of the front doors of a motor vehicle, parts being broken away and certain electrical connections being diagrammatically shown; and

Figure 6 is a fragmentary perspective view of a portion of one of the front vehicle doors showing the preferred location of the push buttons operable for locking the doors.

Referring to Figure 1, the numeral 10 designates a power source, preferably the storage battery of the motor vehicle to which the system is applied, and one terminal of the source is grounded as at 11. The other terminal of the source is connected to a line wire 12 leading to various elements of the system as described in detail below.

The locking system for the vehicle doors comprises a master switch indicated as a whole by the numeral 14 and comprising locking and unlocking solenoids 15 and 16 respectively. These solenoids have associated therewith a swinging armature 17, each end of which forms the armature per se for one of the two solenoids referred to. The armature 17 is provided with any suitable type of off-center spring 18 so as to hold the armature 17 in either of its two positions described below, when moved to either such position by energization of one of the solenoids 15 or 16. A branch wire 20 is connected between the line wire 12 and the armature 17, and this armature carries a contact 21 engageable with a contact 22 when the solenoid 16 is energized to unlock the doors in a manner which will become apparent below.

One terminal of the unlocking solenoid 16 is connected by a branch wire 24 to the line wire 12, and the other terminal of the solenoid 16 is connected to a wire 25 leading to the vehicle door circuits as described below.

One terminal of the locking solenoid 15 is connected to a wire 26 from which a branch wire 27 leads to a switch arm 28. The switch 28 is mechanically associated with the ignition switch referred to above and the switch 28 is engageable with either of a pair of contacts 29 or 30. The contact 29 is tapped into the line wire 12 through a branch wire 31. When the ignition switch is turned off and the key removed from the switch, the switch arm 28 occupies the position shown in Figure 1 in engagement with the contact 29. When the ignition key is in the ignition switch, regardless of whether the ignition is turned on or off, the switch 28 is in engagement with the contact 30 for a purpose to be described.

The contact 30 is connected by a wire 34 to a pair of door jamb switches 35, in series with each other as shown in Figure 1, and connected to a contact 36 forming a part of the ignition switch, the other part being shown as a switch arm 37 connected to the line wire 12. One of the switches 35 is employed in connection with each front door of the vehicle and these switches are in the closed position shown when the doors are closed, and accordingly, it will be apparent that when the engine is running, the switch 37 will be closed, the switch 28 will engage the contact 30 and a circuit from the line wire 12 will be completed to the locking solenoid 15 through the switches 35, wire 34, switch 28 and wires 27 and 26.

The doors are provided with locking mechanisms associated with the parts described above. Inasmuch as the present system is not related to a vehicle having any particular number of doors, the system has been

illustrated in connection with a two-door sedan and the front door electric control devices have been illustrated in Figure 1.

Referring to Figure 1, it will be noted that each front door of the vehicle is provided with a solenoid 40, one terminal of each of which is grounded as at 41. The other terminal of each solenoid is connected as at 42 to a switch 43 tapped into a wire 44 leading to the contact 22. The outside door handles are normally ineffective for releasing the associated latches and are dependent for their operation on the energization of solenoids corresponding to the solenoids 40. To this end, each front door handle, upon initial movement thereof, closes one of the switches 43 to energize the associated solenoid 40 provided the contacts 21 and 22 are in engagement with each other as further referred to below.

The operation of an inside front door handle energizes a solenoid corresponding to the solenoid 16 to restore the door locks to unlocked condition if they have been previously locked. To this end, the wire 25 from the unlocking solenoid 16 is connected to a pair of parallel switches 48 each of which is grounded as at 49. One of the switches 48 will be closed by operation of an inside door handle, and similarly, one of such switches will be closed by inserting the door key in the lock and turning it to unlock the door. Either of two operations, therefore, will energize the unlocking solenoid 16.

The second terminal of the solenoid 15 is connected by a wire 52 to a pair of parallel switches 53 each of which is grounded as at 54. These switches are push button switches and one is arranged in the sill of each front door to be depressed to energize the locking solenoid 15 when it is desired to lock the doors of the vehicle as further described below.

The window regulating portion of the system is shown at the lower part of Figure 1. It will become apparent that while two window regulating mechanisms are shown, duplicates of such mechanisms will be used for each vertically movable window, regardless of whether it is a door window or a window in a stationary part of the vehicle. Each window regulating mechanism in the present instance is shown as comprising a reversible electric motor 60 having wires 61 and 62 leading thereto and energizable in accordance with the desired direction of rotation of the motor, that is, in accordance with whether the window is to be raised or lowered. Each motor 60 is grounded as at 63.

From each motor 60, the wires 61 and 62 are respectively connected to contacts 64 and 65. These contacts are respectively engageable by the armatures 66 and 67 of solenoids 68 and 69. These solenoids have one terminal connected as at 70 to a wire 71. The wire 71 leads through an overload circuit breaker 72 to a wire 73, and this wire is connected through a master overload circuit breaker 74 to the wire 12. In conventional installations, the motors 60 pull thirty-five amperes, and this is usually the capacity of the circuit breakers 72 which are of the type which depend upon heating to break the circuit, and require a number of seconds for their operation when operating at capacity. The circuit breaker preferably is of fifty ampere capacity.

A wire 78 is tapped into the wire 71 of one of the window regulating mechanisms between the circuit breaker 72 thereof and the associated solenoids 68 and 69. The wire 78 leads to a solenoid 79, the second terminal of which is connected to a stationary contact 80 engageable with the armature 81 of an associated solenoid 82 having the same core as the solenoid 79 so that the armature 81 will be in engagement with the contact 80 when either solenoid 79 or 82 is energized. The armature 81 is grounded as at 83.

The armature 81 is also engageable with a pair of contacts 85 connected to wires 86, each of which is connected to a solenoid 69. Each wire 86 has tapped thereinto a contact 87 associated with a switch arm 88 grounded as at 89. Each switch 88 is manually movable into engagement with the associated contact 87 or with a second contact 90 connected by a wire 91 to one of the solenoids 68.

One terminal of the solenoid 82 is connected by a wire 95 to the wire 52 which, as stated, leads to one terminal of the solenoid 15. The second terminal of the solenoid 82 is connected by a wire 96 to one set of

contacts of parallel switches 97, the other contacts of which are connected to the wire 26. The switches 97 are door jamb switches, and when the doors are closed, these switches are open as shown in Figure 1. The switches 97 are biased to closed position so that when either door is opened, the associated switch 97 automatically closes. It is the switches 97, generally speaking, which constitute the means for rendering automatic operation of the window regulating system dependent upon the functioning of the door locking system, as further described below.

As stated, the window regulating system in Figure 1 is of the type wherein reversible electric motors are employed for raising and lowering the windows. A mechanism for utilizing the motors 60 for this purpose is schematically illustrated in Figure 3 wherein one of the motors 60 is illustrated and is provided with a screw shaft 100 operating in a nut 101 having a pin 102 operable in a slot 103 in one arm of a bell crank lever 104. This lever is pivotally supported intermediate its ends as at 105 and has its opposite end connected as at 106 to the window 107. It will be apparent that rotation of the motor in one direction will rock the bell crank lever 104 in a clockwise direction to lower the window 107, while opposite rotation of the motor rocks the bell crank lever counterclockwise to lift the window.

In the system shown in Figure 1, the solenoid 79 operates in conjunction with a holding circuit for the armature 81 after the solenoid 82 has been initially energized. In Figure 2, a slightly modified circuit for this means has been illustrated wherein the wires 95 and 96 are connected to a single solenoid 110, wholly independent of the holding circuit solenoid to be described. The solenoid 110 has an armature 111 grounded as at 112 and engageable, when the solenoid is energized, with a contact 113 connected to a wire 114. This wire leads to a holding circuit solenoid 116, the second terminal of which is connected to the wire 78. The solenoid 116 has an armature 117 grounded as at 118 and engageable with three contacts, one of which is indicated by the numeral 119 and the other two of which are the contacts 85. The contact 119 and wire 114 are connected to the same terminal of the solenoid 116.

In the form of the invention shown in Figure 4, hydraulic motors are employed for raising the windows and springs are employed for lowering the windows, this means per se being conventional and forming no part of the present invention. So far as the door locking system is concerned, the system is the same in Figure 4 as in Figure 1. Accordingly, this system need not be further described and the parts have been indicated by the same numerals in Figure 4.

Referring to Figure 4, the wires 95 and 96, previously described, are connected to a solenoid 125, corresponding generally in function to the solenoid 82 described above. This solenoid has an armature 126, which is not grounded, as is true of the armature 81, for a purpose which will become apparent. Associated with the solenoid 125 and wound on the same core is a holding circuit solenoid 127. The latter solenoid has one terminal connected to a contact 128 engageable with the armature 126. The armature 126 is engageable with three additional contacts in the embodiment of the invention shown, one of such contacts being indicated by the numeral 129 and the other two, for identical purposes, being indicated by the numeral 130.

The line wire 12 in this instance is shown as being connected to parallel switches 133 each of which is movable downwardly into engagement with a contact 134 and upwardly into engagement with a contact 135, the contacts of each such pair being connected to a wire 136 and the two wires 136 being connected to the respective contacts 130. Upward movement of each switch 133 also engages it with a contact 137, in parallel with each other, and connected to a wire 138 from which a branch wire 139 leads to the contact 129.

In the present instance, two vehicle windows 142 have been illustrated and these windows are biased downwardly by springs 143. Upward movement of each window is effected by energizing a hydraulic motor, and each motor is indicated as a whole by the numeral 144. Each hydraulic motor comprises a cylinder 145 having a piston 146 connected at its upper end to one of the windows 142. Each cylinder 145 is provided with a hydraulic fluid

supply line 147 in which is arranged a solenoid valve 148, and each wire 136 is connected to the solenoid of one of these valves, such solenoid being grounded as at 149. The particular window regulating mechanism referred to, including the solenoid valves 148, is conventional and need not be described in detail.

Hydraulic fluid is supplied to the solenoid valves 148 by a pipe 152 connected to a pump 153 supplied with fluid from a reservoir 154. The pump 153 is preferably of the centrifugal type and is driven by a motor 155. One terminal of this motor is connected to the wire 138 and the other terminal is grounded as at 156.

The fluid supply pipe 152 is tapped by a pipe 160 carrying a conventional pressure cut-off switch 161. This switch has its terminals respectively grounded as at 162 and connected to the second terminal of the solenoid 127 by a wire 163.

In Figure 5 of the drawings, I have shown one type of door latch mechanism with which the door locking system is operable and from which the functioning of the electrical systems described above can be more clearly understood. Referring to Figure 5, the numeral 170 designates a door-carried latch plate as a whole bent at an angle to form portions 171 and 172 extending longitudinally and transversely respectively of the motor vehicle. The plate portion 172 is flush with the free edge of the door while the portion 171 lies toward the inner face of the door. The latch device shown in Figure 5 is of the conventional rotary type wherein a device is rotatable by a step-by-step movement to successive locking positions by turning a shaft 173 by a wheel 174 arranged against the inner face of the plate portion 172.

The wheel 174 has a plurality of flat faces 175 each of which has an end 176 projecting beyond the plane of the next adjacent face 175. Successive faces 175 are engageable by the extremity of one arm 177 of a bell crank lever indicated as a whole by the numeral 178 journaled on a pin 179 carried by the plate portion 172. The other arm 180 of the bell crank lever is operable as described below, such arm projecting toward and terminating adjacent the plate portion 171. A leaf spring 181 urges the bell crank lever 178 to turn in a counterclockwise direction as viewed in Figure 5 to the limit of its movement as shown.

A vertically movable plate 184 is provided with a slot 185 in which is slidably a pin 186 fixed to the plate portion 171. Adjacent its lower end, the plate 184 is reduced in size and slides vertically in a guide 187, and the plate 184 is urged upwardly by a leaf spring 188 engaging the lower end of the plate 184 and having one end anchored to the plate portion 171.

The conventional outside door handle, indicated in dotted lines by the numeral 190, is carried by a shaft 191 extending into the door from the outside thereof and having its inner end journaled in the plate portion 171 in accordance with conventional practice. The shaft 191 carries a crank arm 192 engageable with an inwardly extending lip 193 on the plate 184, and such plate is provided with another lip 194 engageable with the top of the lever arm 180. Rotation of the shaft 191 in the direction of the arrow in Figure 5 will cause the arm 192 to tend to move the plate 184 downwardly and transmit movement through the lip 194 to the bell crank lever 178 to free the arm 177 thereof from the wheel 174. Under such conditions, the latch is free to turn upon the pulling of the door handle 190 to open the door, as is well known in conventional practice.

The latch mechanism shown is of the type wherein the outside door handle is immovable when the door is locked. For this purpose, the plate 184 is provided with a shoulder 197 engageable with the upper end of a normally vertical arm 198 of a bell crank lever 199, pivoted to the plate portion 171 as at 200. The other arm 201 of the lever 199 is urged upwardly by a spring 202, and accordingly, the lever 199 is urged to the normal position shown in Figure 5.

The lever arm 201 of each door latch is pivoted as at 205 to the upper end of a depending link 206, the lower end of which is connected to the armature 207 of the magnet or solenoid 40 described above. Energization of the solenoid 40 pulls the link 206 downwardly to turn the bell crank lever 199 to move the upper arm 198 of the lever from beneath the shoulder 197, whereupon the plate 184 is free to move downwardly upon the turning of the

handle 190. Turning movement of the handle 190, as the armature 17 (Figures 1 and 4), is in the unlocked position shown, energizes the solenoid 40 to turn the bell crank lever 199. To this end, the plate 184 at its upper end carries a vertical projection 210 normally engaging the button 211 of the switch 43 described above. This switch is biased to closed position but is normally maintained open by engagement of the projection 210 with the button 211. When the handle 190 is initially turned, the button 211 is released and the switch 43 closes to energize the circuit through wires 44 and 42 and thence through solenoid 40, as further described below.

The pin 186 pivotally supports a lever 215 having a projection 216, overlying the lever arm 180. Rotation of the lever 215 counterclockwise in Figure 5 will cause the end 216 thereof to move the lever arm 180 downwardly in the same manner as this operation is performed by the lip 194.

The lever 215 is pivotally connected at 217 to one end of a link 218, the other end of which is connected as at 219 to a crank 220 mounted on a shaft 221 carrying the inside door handle 222. The shaft 221 is supported by a plate 223 carried by the door, and a leaf spring 224 tends to turn the crank 220 counterclockwise in Figure 5 to maintain the lever 215 in the normal position shown.

A shaft 226 is provided adjacent its outer end with the usual door key-controlled lock (not shown). A cam 227 is carried by the shaft 226 and engages one arm 228 of a bell crank lever 229 pivoted to the plate 170 by a pin 230. The other arm 231 of this bell crank lever is connected by a link 232 with the lever 215 through a slot and pin connection 233. The lever arm 231 is adapted to operate the push button 234 of the switch 48 described above. The switch 48 is biased to closed position but is normally held in open position by a lip 235 on the lever arm 231.

A link 238 is pivoted at one end to the pin 239 and is connected at its opposite end as at 239 to the link 206. A small pin 240, carried by the lever arm 231, overlies the link 238 to transmit a downwardly pulling force to link 206 upon clockwise turning movement of the bell crank lever 229 incident to operation thereof by the cam 227 when the door is unlocked by the key shaft 226 when the inside door handle 222 is rotated to unlock the door.

In Figure 6, a portion of one of the front doors of a motor vehicle has been illustrated showing a conventional arrangement for each of the switches 53. This switch may be mounted beneath the sill 245 of the door 246 with the button 247 for the switch projecting upwardly through the sill to be readily accessible.

Operation

The operation of the system in Figure 1 will be first described as a whole. Assuming that the master switch armature 17 is in the unlocked position in Figure 1 from a previous energization of the unlocking solenoid 16, all doors of the vehicle are unlocked and may be opened by the outside door handles. Under such conditions, movement of one of the front door handles will close the associated switch 43 by downward movement of the plate 184 (Figure 5) incident to turning movement of the handle 190. Current will flow from the source through wires 12 and 20, armature 17, wire 44, the operated switch 43, through the associated solenoid 40 and back to the source through grounds 41 and 11. Energization of such solenoid 40 conditions the latch of the door to render the outside door handle effective for unlatching the door by rocking the bell crank lever 199 to move the arm 198 outwardly from beneath the shoulder 197 (Figure 5).

Assuming that the armature 17 is in the unlocked position shown in Figure 1 and the driver is in the driver's seat with the engine running and desires to prevent entrance into the vehicle, the driver will operate the switch 53 in the left door by pressing the button 247 (Figure 6). Under the conditions stated, the ignition switch 37 will be closed, the switches 35 will be in the normally closed position for the reason that the doors are closed, and the switch arm 28 will be in engagement with the contact 30. Upon operation of one switch 53, therefore, current will flow from the source through wire 12, switches 37 and 35, wire 34, switch 28, wires 27 and 26 through solenoid 15, thence through wire 52, the op-

erated switch 53 and back to the source through grounds 54 and 11. The solenoid 15 thus will be energized, swinging the armature 17 to the locked position, disengaging the contact 21 from the contact 22. Thus no circuit can be completed through wire 44 to either of the outside door handle operated switches 43, and accordingly, no one can enter the vehicle. Thus the driver will be protected from so-called "redlight bandits."

Assuming that the driver desired to leave the vehicle and lock the doors, disregarding for the time being the window regulating system, the turning of the ignition switch key to "off" position opens the switch 37, and removal of the ignition key moves the switch 28 into engagement with the contact 29. One means for controlling the switch 28 by movement of the ignition key is shown in my prior patent, No. 2,506,851, granted May 8, 1950. A circuit through the locking solenoid 15 can now be completed by operating one of the switches 53 (push button 247, Figure 6), through the wire 31, switch 28, wire 26, etc., instead of through the initial path described above, which includes the ignition switch 37. Upon leaving the car under such conditions, therefore, the operator, by closing one of the switches 53, will energize the solenoid 15 to disconnect the contact 21 from contact 22, whereupon all of the doors of the car will be locked from the outside.

Assuming that the operator turns off the ignition switch but fails to remove the key from the switch, then the switch 28 will remain in engagement with the contact 30. No circuit can be completed under such conditions through solenoid 15 since both initial circuit paths therefor will be broken, one at the contact 29 and the other at the open ignition switch 37. Thus the operator will be advised that he has left the key in the ignition switch, whereupon he will remove the key, causing the switch 28 to engage the contact 29 to render either switch 53 operative for locking the car.

In the event the operator attempts to lock the car with the ignition switch closed, regardless of whether the engine is running or not, the car cannot be locked, since when the operator steps from the car, one of the switches 35 will automatically open when the door is opened, thus breaking any circuit through wire 34.

The operator, upon returning to the car, can insert the key in either door lock and turn it. This operation rotates the shaft 226 (Figure 5) in the direction of the arrow, and the cam 227 engages the end of the arm 228 to swing the lever 229 clockwise, whereupon the lip 235 presses the button 234 to close the associated switch 48. This closes a circuit through the unlocking solenoid 16 through wires 12, 24 and 25, the operated switch 48 and grounds 49 and 11. Each switch 48 is also controlled by the inside door handle of the associated door to be closed whenever an inside door handle is operated. Referring to Figure 5, rotation of the inside door handle 222 pulls link 218 and rocks the lever 215 to turn the lever 178 to release the latch wheel 174. Rocking of the lever pulls downwardly on link 232 to rock the lever 229 and press the button 234 in the same manner as when unlocking the door with a key. If the operator has previously locked the doors from the outside, the operation of an inside door handle, when leaving the car, will thus energize the unlocking solenoid, accordingly moving the armature 17 to the position shown in Figure 1 to restore the normal conditions of the parts.

Assuming that the operator is in the car with the doors closed, regardless of whether the car is running or standing still, the operator may control either of the windows through the associated motor 60. Assuming that the operator desires to raise a window, he will raise one of the switches 88 into engagement with the associated contact 87. Current will then flow through wire 12, circuit breaker 74, wire 73, through the associated circuit breaker 72, wires 71 and 70, through solenoid 69, wire 86, contact 87, switch arm 88 and back to the source through grounds 89 and 11. When the window has been raised sufficiently, the switch 88 will be released to return to its normal position between the contacts 87 and 90, to which position it is biased.

Assuming that the window is to be lowered, the switch 88 will be moved downwardly into engagement with the contact 90. Current will then flow through the path last described to the wire 70, thence through solenoid 68, contact 90, switch 88 and grounds 89 and 11. When the

window has been lowered to the desired extent, the operator releases the switch 88.

The overload switches 72 are for the purpose of preventing damage to the motor and other parts and undue drains on the battery by automatically cutting off the current to either motor 60 after either window has moved to its limit of movement and has been in such position for several seconds. These overload switches operate in this manner either for the manual controlling of the windows or the automatic controlling of the windows in conjunction with the door locking mechanisms, as further described below.

The automatic operation of the window regulating mechanisms is dependent upon the closing of either switch 97. These switches are biased to closed position but are maintained open when the doors are closed, which is the condition illustrated in Figure 1. It will become apparent, therefore, that the manual operation of the windows with the doors closed takes place as referred to above, without interference or control by the door locking system. Similarly, the operator can lock the doors while within the car with the doors closed without affecting the window regulating system.

Assuming that the operator desires to leave the vehicle and lock it, he will perform the locking operations referred to above.

Assuming that the foregoing operations are carried out, the switch 28 will engage the contact 29, and when either door is opened, its associated switch 97 will be closed. Current will flow through the locking solenoid 15 in the manner previously described, and in addition, current will flow through wire 26, the switch 97 of the opened door, such switch now being closed, thence through wire 96, solenoid 82 and wire 95 through the rest of the circuit including the wire 52 and the actuated push button 53. Thus the energization of the solenoid 82 is dependent upon two conditions, namely, the pushing of one of the buttons 53 to lock the car and the opening of one of the doors to close the switch 97. It will become apparent, therefore, that if the operator leaves the car without depressing one of the push buttons 53, the solenoid 82 will not be energized and the window regulating system will be unaffected.

Assuming that the solenoid 82 has been energized by the closing of one switch 97 and the operation of one of the push buttons 53, the armature 81 will move into engagement with contacts 80 and 85. Under such conditions, a holding circuit will be provided for the armature 81 through wire 12, circuit breaker 74, wire 73, the left hand circuit breaker 72, wire 78, solenoid 79, contact 80 and armature 81, and thence back to the source through grounds 83 and 11. The armature 81 thus will be held in engagement with its three contacts.

Current will then flow through line wire 12, circuit breaker 74, both circuit breakers 72, and through both window regulating mechanisms through the wires 71 and 70 and solenoids 69 thereof, and thence through the two wires 86, contacts 85, armature 81 and ground 83. Even though the opened door is immediately closed before the windows are raised, the holding circuit solenoid 79 will maintain closed the circuits through the solenoids 69, to keep the switches 67 closed and maintain energization of the motors 60 until the windows are closed.

In conventional practice, the motors 60 draw thirty-five amperes, which is preferably the capacity of the circuit breakers 72. These circuit breakers open by heating and require five to nine seconds to open, whereas the windows are movable from fully open position to fully closed position in less than two seconds. Thus the motor 60 will be maintained energized more than the length of time necessary to close the windows, after which either or both circuit breakers 72 will be opened, and if this fails to occur, the circuit breaker 74 will open. The capacity of the circuit breaker 74 is preferably fifty amperes, which is less than double the capacity of each breaker 72. Such approximate capacity of the circuit breaker 74 is preferred to insure the opening of the main circuit through wire 12 in the event of sticking of either circuit breaker 72. One of the circuit breakers, in this instance the left hand circuit breaker in Figure 1, is preferably arranged between the wires 73 and 78. If current flowed directly between these wires and the breaker referred to were arranged above the wire 78, there would be a possibility that the circuit breakers 72 might alternately open and close as they heated and cooled, thus

intermittently energizing the motors. By arranging the left hand circuit breaker as shown, the breaking of the circuit therethrough momentarily will open the holding circuit through solenoid 79. Of course, upon the breaking of the holding circuit, both solenoids 69 will be immediately deenergized and their armatures 67 will return to the positions shown, thus opening the circuits through the two motors 60. Upon the breaking of the holding circuit, the armature 81, of course, will return to open position as shown in Figure 1, the solenoid 82 being also deenergized through the opening of the switches 97 upon the closing of the doors and the switches 53, of course, being open.

The alternate circuit shown in Figure 2 need not be described in detail. Instead of using the tandem solenoids 79 and 82 with a common core, separate solenoids 110 and 116 are used. When a door is opened to close the associated switch 97 and one of the push buttons 53 is momentarily operated, the solenoid 110 will be energized to move the switch 111 into engagement with contact 113. As described in connection with the solenoid 79, the solenoid 116 will then be energized to attract its armature 117, the circuit being closed through wires 78 and 114, switch 11 and grounds 112 and 11. Upon energization of the solenoid 116, its circuit will be grounded through contact 119, switch 117 and ground 118, and accordingly, it is necessary only momentarily to energize the solenoid 110. The solenoid 116, therefore, has its own holding circuit which will remain closed until the circuit through wire 78 is opened by the overloading of the circuit breakers in the magnet described.

In the form of the invention shown in Figure 4, the locking circuit is identical with that described and the circuit through wires 95 and 96 and solenoid 125 is closed in exactly the same manner as the circuit through solenoid 82, described above. A circuit is closed through the holding circuit solenoid 127 upon energization of the solenoid 125 to engage armature 126 with contact 128, except that the circuit for the holding solenoid 127 is grounded at 162 through the normally closed pressure cut-off switch 161. When the car is to be locked when the driver leaves the vehicle, the holding circuit solenoid 127 will maintain a circuit closed through wire 12, switch 126, contact 129, wire 138 through motor 155 and its ground. The motor 155 will then come into operation and the pump 153 will pump hydraulic fluid through pipe 152. At the same time, parallel circuits will be closed from armature 126 through contacts 130, wires 136, and solenoid valves 148 and back to ground as at 149. The solenoid valves will be opened and the pumped fluid will flow from pipe 152 through pipes 147 into the cylinders 145. As each window closes, fluid will stop flowing into its associated cylinder 145, and when both of the windows are completely closed, an increased static pressure will be built up in the fluid system to open the pressure cut-off switch 161 and break the circuit through the holding solenoid 127. The circuit for the motor 155 will then be broken at the contact 129. At the same time, the circuits through the solenoid valves 148 will be opened at the contacts 130, and these valves will be closed.

The switches 133 provide for the conventional manual controlling of the window regulating mechanisms. So long as the armature 126 is in the normal position shown, in which position it remains unless the car is to be locked, the operator can move either switch 133 upwardly to engage the associated contacts 135 and 137. Current will then flow through wire 12, switches 133, contacts 135 and wires 136 to energize the solenoid valves 148 and open them. Simultaneously, a parallel circuit will be established through the associated contact 137, wire 138 and motor 155 to start the pump 153 to force fluid into the associated cylinder 145. The releasing of the previously operated switch 133 opens the circuits referred to and the window will stop at the point desired.

Downward movement of either switch 133 engages it with its contact 134 which closes a circuit through the associated solenoid valve 148 in the same manner as when the contact 135 is engaged, but the motor 155 will not be energized. The opening of one of the solenoid valves 148 releases fluid from the associated cylinder 145 to return to the reservoir 154 through pipe 152 and through the pump 153, the springs 143 pulling the window downwardly. When the window has opened to the desired point, releasing of the switch 133 results in the closing of the previously operated solenoid valve 148, thus

trapping fluid in the cylinder 145 and holding the window in the desired position.

From the foregoing, it will be apparent that the present system provides all of the advantages of the door locking mechanisms and permits the window regulating devices to be operated wholly independently of the locking system, when desired, for example when the vehicle is occupied and it is desired to raise or lower one or more windows. However, the door and window regulating systems become interdependent when it is desired to leave the car and lock it. Thus the two systems, when desired, are interdependent, and in order to operate both systems, it is necessary for the operator to perform only two operations, namely the pushing of one button 53 and the opening of the car door, which latter operation is necessary in any event for the occupant to leave the car. Essentially, therefore, only one operation is needed other than the actions normally performed, namely, the closing of one switch by operation of a single push button which results in the locking of all of the doors and the closing of all of the windows of the car.

I claim:

1. A vehicle door locking and window regulating system comprising a mechanism connected to the vehicle doors and operable from within the vehicle for locking the doors against entrance from the outside, a window regulating mechanism connected to a vehicle window and operable from within the vehicle for regulating said window of the vehicle, an electric circuit connected to control said window regulating mechanism, a switch in said circuit biased to closed position and normally held in open position by one of the vehicle doors when the latter is closed, and means connected to said door locking mechanism and to said one door and operative upon operation of said door locking mechanism and upon the opening of said one door, whereby said switch closes, for rendering said window regulating mechanism operative for closing said vehicle window.
2. A vehicle door locking and window regulating system comprising an electric circuit, means comprising a switch in said circuit accessible within the vehicle for rendering said circuit operative for preventing the opening of the vehicle doors from the outside, power means connected to each of a plurality of the vehicle windows for vertically moving such windows to regulate them, manually operable means connected to said power means for rendering such means operative to individually regulate such vehicle windows, and means having mechanical connection with one of the vehicle doors and operative when said circuit is rendered operative by the closing of said switch and one of the vehicle doors is opened for rendering said power means operative independently of said manual means for closing all of the vehicle windows associated with said power means.
3. A vehicle door locking and window regulating system comprising an electric circuit, means comprising a switch in said circuit accessible within the vehicle for rendering said circuit operative for preventing the opening of the vehicle doors from the outside, power means connected to each of a plurality of the vehicle windows for vertically moving such windows to regulate them, manually operable means connected to said power means for rendering such means operative to individually regulate such vehicle windows, and a second electric circuit energizable for rendering said power means operative for closing all of the vehicle windows associated therewith, said second circuit being dependent in part for its energization on the energization of said first named circuit upon the operation of said switch, said second circuit including a second switch biased to closed position and normally held in open position by one of the vehicle doors whereby, when said first mentioned switch is operated and said one door is opened to release said second switch for movement to closed position, said second circuit will be energized.
4. A door locking and window regulating system comprising a master switch, means connected to said master switch and to the vehicle doors and controlled by said master switch for locking and unlocking the vehicle doors against entrance from the outside, operating means connected to said master switch and including a switch accessible within the vehicle for operating said master switch for locking the vehicle doors, a power window operator connected to each of a plurality of the vehicle windows, manual means connected for individually controlling said power operators, and means in addition to said manual

means, connected to said power operators, and operative when said master switch is in position for locking the vehicle doors and one of the vehicle doors is opened for rendering all of said power operators operative for closing their associated windows, said last named means including an element biased to an operative position and held in a normal inoperative position by said one door when the latter is closed.

5. A door locking and window regulating system comprising a master switch, means connected to said master switch and to the vehicle doors and controlled by said master switch for locking and unlocking the vehicle doors against entrance from the outside, operating means connected to said master switch and including a switch accessible within the vehicle for operating said master switch for locking the vehicle doors, a power window operator connected to each of a plurality of the vehicle windows, manual means connected for individually controlling said power operators, and means comprising an electric circuit including said master switch and another switch biased to closed position and normally held open by one of the vehicle doors, whereby said electric circuit is dependent for its operation on the opening of said one of the vehicle doors and movement of the master switch to door-locking position for rendering all of said power operators operative for closing their associated windows.

6. A door locking and window regulating system comprising a master switch, means connected to be controlled by said master switch for locking and unlocking the vehicle doors against entrance from the outside, means connected to control said master switch, comprising a switch accessible within the vehicle for operating said master switch for locking the vehicle doors, a power window operator connected to each of a plurality of the vehicle windows, manual means connected for individually controlling said power operators, an operating circuit connected to said power operators and energizable for rendering all of said power operators operative for closing their associated windows, a control circuit including said master switch and another switch biased to closed position and normally held open by one of the vehicle doors, whereby said control circuit is energizable upon opening movement of said one of the vehicle doors and upon movement of said master switch to door-locking position for initiating the energization of said operating circuit, holding means connected to said operating circuit for maintaining said operating circuit closed after it has been initially closed, and means connected to be controlled by closing of the windows for opening said operating circuit after all the windows associated with said power operators have been closed.

7. A door locking and window regulating system comprising a master switch, means connected to be controlled by said master switch for locking and unlocking the vehicle doors against entrance from the outside, means connected to control said master switch, comprising a switch accessible within the vehicle for operating said master switch for locking the vehicle doors, a power window operator connected to each of a plurality of the vehicle windows, manual means for individually controlling said power operators, an operating circuit connected to said power operators and energizable for rendering all of said power operators operative for closing their associated windows, a control circuit including said master switch and another switch biased to closed position and normally held open by one of the vehicle doors, whereby said control circuit is energizable upon opening movement of said one of the vehicle doors and upon movement of said master switch to door-locking position for initiating the energization of said operating circuit, holding means connected to said operating circuit for maintaining said operating circuit closed after it has been initially closed, a source of power for said power operators, and overload means connected to be responsive to the overloading of said power source incident to the stopping in closed position of all of the windows associated with said power operators for cutting off the supply of power to said power operators.

8. A vehicle door locking and window regulating system comprising a circuit including a master switch having a locking electromagnetic device and an unlocking electromagnetic device, means connected in said circuit to close it for rendering the doors capable of being opened from the outside after energization of said unlocking device and for maintaining said circuit open, whereby the

doors are incapable of being opened after energization of said locking device, a first switch and a second switch connected in and operable for closing circuits respectively through said locking and unlocking electromagnetic devices, a power operator connected to each of a plurality of the vehicle windows, manually operated mechanisms connected for individually controlling said power operators, and means having connection with said power operators and with one vehicle door and operable when said first switch is closed and said one of the vehicle doors is opened for rendering all of said power operators operative for closing the vehicle windows.

9. A vehicle door locking and window regulating system comprising a circuit including a master switch having a locking electromagnetic device and an unlocking electromagnetic device, means connected to said circuit to close it for rendering the doors capable of being opened from the outside after energization of said unlocking device and for maintaining said circuit open, whereby the doors are incapable of being opened after energization of said locking device, a first switch and a second switch connected in and operable for closing circuits respectively through said locking and unlocking electromagnetic devices, a power operator connected to each of a plurality of the vehicle windows, manually operated mechanisms connected for individually controlling said power operators, a source of power for said power operators, means having connection with said power operators and with one vehicle door and operative upon the closing of said first switch and the opening of said one of the vehicle doors for rendering said power operators operative for moving all of the windows associated therewith to closed position, and means connected to be responsive to operation of the windows to be operative when said windows reach closed position for rendering said power source ineffective for supplying power to said power operators.

10. A vehicle door locking and window regulating system comprising a circuit including a master switch having a locking electromagnetic device and an unlocking electromagnetic device, means connected to said circuit to close it for rendering the doors capable of being opened from the outside after energization of said unlocking device and incapable of being opened after energization of said locking device, a first switch and a second switch connected in and operable for closing circuits respectively through said locking and unlocking electromagnetic devices, the circuit for said locking electromagnetic device having a parallel circuit including a control switch biased to closed position and normally maintained in open position by one of the vehicle doors when such door is closed, a power operator connected to each of a plurality of the vehicle windows, individually operable manual means connected for controlling the operation of said power operators, and means having connection with said power operators and with one vehicle door and operative upon the closing of said circuit for said locking electromagnetic device by operation of said first switch and the closing of said parallel circuit by the releasing of said control switch upon the opening of said one door for rendering all of said power operators operative for closing all of the vehicle windows associated with said power operators.

11. A vehicle door locking and window regulating system comprising a circuit including a master switch having a locking electromagnetic device and an unlocking electromagnetic device, means connected to said circuit to close it for rendering the doors capable of being opened from the outside after energization of said unlocking device and incapable of being opened after energization of said locking device, a first switch and a second switch connected in and operable for closing circuits respectively through said locking and unlocking electromagnetic devices, the circuit for said locking electromagnetic device having a parallel circuit including a control switch biased to closed position and normally maintained in open position by one of the vehicle doors when such door is closed, a power operator connected to each of a plurality of the vehicle windows, individually operable manual means connected for controlling the operation of said power operators, electric circuit means connected to be energizable for rendering all of said power operators operative for closing the vehicle windows associated therewith, and means operative for energizing said electric circuit means upon operation of said first switch to energize said locking electromagnetic device and upon

the opening of said one door to release said control switch for movement to closed position.

12. A vehicle door locking and window regulating system comprising a circuit including a master switch having a locking electromagnetic device and an unlocking electromagnetic device, means connected in said circuit to close it for rendering the doors capable of being opened from the outside after energization of said unlocking device and for maintaining said circuit open whereby the doors are incapable of being opened after energization of said locking device, a first switch and a second switch connected in and operable for closing circuits respectively through said locking and unlocking electromagnetic devices, the circuit for said locking electromagnetic device having a parallel circuit including a control switch biased to closed position and normally maintained in open position by one of the vehicle doors when such door is closed, a power operator connected to each of a plurality of the vehicle windows, individually operable manual means connected for controlling the operation of said power operators, a relay comprising an electromagnetic coil in said parallel circuit and an armature therefor, and a control circuit connected to be energizable for rendering said power operators operative for closing all of the windows associated therewith, said control circuit having contacts engageable by said armature when said relay is energized.

13. A system constructed in accordance with claim 12 wherein said control circuit further includes a holding circuit connected to be energized for maintaining said control circuit operative after said relay has been energized, and means connected to be responsive to operation of the windows for breaking said holding circuit after all of the windows associated with said power operators have reached closed position.

14. Apparatus constructed in accordance with claim 12 wherein said control circuit includes a holding circuit connected to be energized for maintaining it energized after said relay has been deenergized, a source of power connected to said power operators, and means connected to be responsive to operation of the windows and operative after all of the windows associated with said power operators have reached closed position for rendering said power source ineffective for supplying power to said power operators.

15. A door locking and window regulating mechanism for a motor vehicle having a plurality of doors and a plurality of vertically movable windows, comprising a regulating device for each of the windows including a power device, means connected to each power device to render it operative, including a manual control element, a door locking device for each of the vehicle doors, a manually movable device connected to each locking device, a master control system connected to each manually movable device to be operable by any such device for

locking or unlocking all of the doors, and a second system connected to all of said window regulators and operative for rendering all of said power devices simultaneously operative for closing all of the windows, said second system comprising a control device connected to one of the vehicle doors and normally held inoperative when such door is closed and being biased to an operative position to move to such position when the door is opened, said control device being connected to one of said manually movable devices to be rendered operative for energizing all of said power devices only when such manually movable device is moved to lock all of the vehicle doors.

16. A door locking and window regulating mechanism for a motor vehicle having a plurality of doors and a plurality of vertically movable windows, comprising a regulating device for each of the windows including a power device, means connected to each power device to render it operative, including a manual control element, a door locking device for each of the vehicle doors, a manually movable device connected to each locking device, a master control system connected to each manually movable device to be operable by any such device for locking or unlocking all of the doors, and a second system connected to all of said window regulators and operative for rendering all of said power devices simultaneously operative for closing all of the windows, said second system comprising a control switch connected to one of the vehicle doors and normally held open when such door is closed and being biased to a closed position to move to such position when the door is opened, said manually movable devices comprising switches connected in parallel and said control switch being connected in series to said parallel-connected switches to be rendered operative for energizing all of said power devices only when said manually movable device is moved to lock all of the vehicle doors.
